UNITED STATES PATENT OFFICE.

JOSHUA DAVIES, OF MUSKEGON, MICHIGAN.

DESIGN FOR HITCHING-POST.

Specification forming part of Design No. 7,799, dated October 13, 1874; application filed October 1, 1874.
 [Term of Patent 7 years.]

CASE A.

To all whom it may concern:

Be it known that I, JOSHUA DAVIES, of Muskegon, in the county of Muskegon and State of Michigan, have invented a Design for Cast-Iron Hitching-Posts, of which the following is a specification:

The nature of my design is fully represented in the accompanying photographic illustration, to which reference is made.

A represents a circular base, consisting of a molding resting on a flat circular plate. B is a tapering octagonal column rising from the

pediment, having a sunken panel on each face, with a bead at the base of the flaring capital, which supports a spaniel dog's head, C, whose neck rises from a fluted base, which forms a contracted continuation of the capital.

What I claim as my invention is—

The design for a hitching-post, substantially as represented and described.

JOSHUA DAVIES.
